DESIGN FOR A PHYSIOTHERAPY TABLE

Bernard H. Stauffer, Los Angeles, Calif.

Application July 15, 1940, Serial No. 93,652

Term of patent 14 years

To all whom it may concern:

Be it known that I, Bernard H. Stauffer, a citizen of the United States of America, residing at Los Angeles, in the county of Los Angeles, State of California, have invented a new, original, and ornamental Design for Physiotherapy Tables, of which the following is a specification, reference being had to the accompanying drawing, forming a part thereof.

Figure 1 is a side elevational view of a physiotherapy table showing my new design.

Figure 2 is an end elevational view thereof.

The opposite side and end of the table are substantially the same as the side and end shown in the drawing.

I claim:

The ornamental design for a physiotherapy table, as shown and described.

BERNARD H. STAUFFER.
